UNITED STATES PATENT OFFICE.

LARS N. HOLM, OF DES MOINES, IOWA.

STEAM-ENGINE.

SPECIFICATION forming part of Letters Patent No. 657,113, dated September 4, 1900.

Application filed February 2, 1900. Serial No. 3,698. (No model.)

To all whom it may concern:

Be it known that I, LARS N. HOLM, a citizen of the United States, residing at Des Moines, in the county of Polk and State of Iowa, have 5 invented certain new and useful Improvements in Steam-Engines, of which the following is a specification.

The object of this invention is to provide a simple, strong, durable, and inexpensive 10 steam-engine that may be operated by a minimum of steam to produce a maximum of power to the end that an effective engine may be produced at less cost than other engines of corresponding efficiency.

15 My invention consists in certain details in the construction, arrangement, and combination of the various parts of the engine whereby the object contemplated is attained, as hereinafter more fully set forth, pointed out 20 in my claims, and illustrated in the accompanying drawings, in which—

Figure 1 shows a transverse section of the engine through the indicated line 1 1 of Fig. 2. Fig. 2 shows a longitudinal section of the 25 engine through the indicated line 2 2 of Fig. 1. Fig. 3 shows in perspective the shaft and one of the oscillating pistons and the partitions for dividing the two chambers of the engine. Fig. 4 shows a like view of the other piston. 30 Fig. 5 shows in side elevation one of the steam-tight packing devices. Fig. 6 shows a plan of same, and Fig. 7 shows in perspective one of the cranks to be attached to the piston-hubs.

35 Referring to the accompanying drawings, I have used the reference-numeral 10 to indicate a steam-cylinder of ordinary construction and having at its ends the detachable heads 11. At the bottom of the cylinder is a 40 base 12, and at the top of the cylinder is an integral flat-topped extension 13. This flat-topped extension 13 is for the purpose of supporting the steam-chests, which will be hereinafter described. It is to be understood that 45 the cylinder is divided into two equal compartments by a partition which will be hereinafter fully described. In each of the compartments thus formed I have fixed an abutment (indicated by the numeral 14) and ex- 50 tending from a point about thirty degrees from a central line at the top of the cylinder

to a point about the same distance from a central line on the opposite side of the cylinder. This abutment is held in position by screws passed through the cylinder, and its 55 central portion is rounded out to admit the hubs of the pistons hereinafter described.

Referring to Fig. 3 of the drawings, the engine-shaft is indicated by the numeral 15 and is of a length to project through both cylinder-heads. Keyed to the central portion of said shaft is a disk-shaped partition 16, having an expansion packing-ring 17 therein. The periphery of this disk is designed to engage the interior of the cylinder. On 60 one end of the shaft is a piston-hub 18, with an integral collar 19 thereon to project through the cylinder-head. This hub is keyed to the shaft by means of the key 20, and at its top the piston 21 is formed integrally to project straight outwardly and to 65 extend to the interior surface of the cylinder. This piston is provided with a central opening 22, into which a packing device is placed. This packing device, which is clearly illustrated in Figs. 5 and 6, comprises two steel 70 strips 23 and 24, each bent at right angles at its central portion and the strip 23 being provided with an extension 25, designed to enter the bifurcated end 26 of the opposite strip. 75 Extensile coil-springs 27 are interposed between the interior of the piston and the outer portions of the said parts 23 and 24, and like springs 28 are interposed between the piston 80 and the end portions of the parts 23 and 24, so 75 that said parts are normally pressed to their limit of movement in a direction at right angles to the hub and longitudinally of the hub, and obviously the joint between the parts 23 and 24 may expand without permitting a leak- 85 age of steam at the joint. It is obvious that instead of keying the partition 16 and the hub 18 to the shaft 15 the entire device, comprising the parts 15, 16, and 18, may be formed integral in one piece. At the other end of 90 the shaft 15 and within the cylinder I have mounted a hub 29 loosely upon the shaft, with its one end in engagement with the partition 16 and its other end provided with the tubular extension 30, corresponding to the exten- 95 sion 19 on the part 18. This hub 29 is also 100 provided with a piston 31, and a packing de-

vice 32, similar to the packing device in the piston 21, is placed therein. On the extension 19 I have mounted a crank-arm 33, held in place by means of the screws 34, so as to 5 operate in unison with the hub 18. On the extension 30 I have mounted the crank-arm 35 by means of the screws 36, the said shaft 15 being permitted to rotate freely within the crank-arms. This crank-arm 35 is set at an 10 angle of about thirty degrees from the position of the crank-arm 33. At the joints between the cylinder-heads 11 and the extensions 19 and 30 I have provided the packing-boxes 37, of ordinary construction, and the 15 screws 38 provide means for adjusting the packing. Upon the said extension 13 I have mounted the steam-chest 40. This steam-chest 40 is divided by a central transverse partition 41 into two separate chambers, and 20 I have provided means for admitting steam from a boiler direct to these steam-chambers, as follows: The reference-numeral 42 indicates a block supported by screws 43 in the central portion of the top of the chest. A 25 steam-pipe 44 is inserted in a block 45, which is held by means of screws to the block 42, and in this block 42 are the two passage-ways 46, leading from the pipe 44 to the steam-chambers. It is obvious that by means of the 30 detachable block or plate 45 packing devices may be interposed under the said block or plate to prevent the escape of steam, and this part may be readily detached at any time to adjust the packing.

35 In each of the steam-chambers within the chest is a D-valve 47, of ordinary construction, each valve being operated by a rod 48, passed through the side of the steam-chest. In the extension 13 are two passage-ways 49, 40 leading from the interior of the steam-chamber to points within the interior of the cylinder at the edges of the block 14, and between these passage-ways is an exhaust-opening 50, leading outwardly toward the ends of the 45 cylinder to points of discharge. The operation of the valve is similar to that of the ordinary reciprocating engine, and in use the steam in the chest will pass downwardly through one of the passage-ways 49 when 50 the D-valve is moved and will force the piston toward the other side of the cylinder. The steam in the other side will then pass upwardly through the remaining passage-way 49 and then outwardly through the exhaust-opening 50. Then when the piston reaches 55 the abutment the D-valve will be so operated by mechanism (not shown) as to admit the steam through the passage-way 49 on the side to which the piston is inclined, and by 60 the same process the piston will be returned to its original position. It is obvious that the length of stroke of the pistons may be changed by making the abutment 14 smaller or larger, and, furthermore, the two separate 65 engines on the same shaft may be made to operate on the double-expansion principle

by changing the arrangement of supply and exhaust steam pipes, if desired. It is obvious, further, that a double steam-engine made on this principle will have fewer parts, 70 and hence be cheaper to manufacture than the ordinary steam-engine, and, furthermore, it will be obvious that a maximum of power may be obtained by the use of a given quantity of steam on account of the slight amount 75 of friction necessarily involved in the operation of the engine and on account of the fact that the steam-pressure is applied to the piston at a point distant from the pivotal points thereof. Hence an advantage of leverage is 80 obtained.

Having thus described my invention, what I claim, and desire to secure by Letters Patent of the United States therefor, is—

1. An improved steam-engine, comprising 85 in combination, a cylinder, a shaft to pass centrally through the cylinder, a hub rigidly mounted on one end of the shaft, an extension on the said hub, projected through the cylinder-head, a piston formed on or fixed to 90 the hub, a disk-shaped partition formed on or fixed to the central portion of the shaft, a hub rotatably mounted upon the other end of the shaft within the cylinder, an extension on the hub projected through the other cylinder-head, a piston on the said latter hub, and two 95 abutments fixed in the interior of the cylinder on opposite sides of the central partition, and means for controlling the steam induction and exhaust from the steam-chambers, substantially 100 as, and for the purposes stated.

2. An improved steam-engine, comprising 105 in combination, a cylinder, a shaft rotatably mounted in the cylinder, a hub formed in or fixed to the shaft, a piston on the hub, a disk-shaped partition formed on or fixed to the hub, a crank detachably fixed to the hub, a second hub rotatably mounted on said shaft, a piston on said hub, two separate abutments fixed 110 in the cylinder, and means for controlling the passage of steam to and from the cylinder on the opposite sides of said partition.

3. An improved steam-engine, comprising 115 in combination, a cylinder, detachable cylinder-heads thereon, a shaft to pass centrally through the cylinder, a hub formed on or fixed to one end of the shaft, an extension on the said hub to pass through cylinder-head, a crank-arm detachably fixed to said extension, a piston formed on or fixed to the hub, a disk-shaped partition formed on or fixed to the central portion of the shaft, a hub rotatably mounted upon the other end of the shaft, an extension on the hub to project through the other cylinder-head a crank-arm detachably 125 secured to said extension, a piston formed on or fixed to said latter hub, and two abutments 130 fixed to the interior of the cylinder on opposite sides of the central partition, and means for controlling the admission of steam to and from the steam-chambers, thus formed, substantially as, and for the purposes stated.

4. In a steam-engine, the combination of a steam-chest, a central partition 41 in the steam-chest, a D-valve on each side of said partition, a block 42 having the passage-ways 46 therein, detachably secured to the top of the central portion of the steam-chest, a detachable plate 45 in the top of the steam-chest secured to said block 42, and a steam-induction pipe in the said plate 45, substantially as, and for the purposes stated.

LARS N. HOLM.
